UNITED STATES PATENT OFFICE

TOM R. BROWN, OF KENNETT SQUARE, PENNSYLVANIA, ASSIGNOR TO THE GLACIFER CORPORATION, OF KENNETT SQUARE, PENNSYLVANIA, A CORPORATION OF DELAWARE.

SHIPPING CONTAINER

Application filed March 9, 1928. Serial No. 260,470.

This invention relates to certain improvements in shipping containers; and the nature and objects of the invention will be readily recognized and understood by those skilled in the arts involved in the light of the following explanation and detailed description of the accompanying drawings illustrating what I at present consider to be the preferred embodiment or mechanical expression of my invention from among various other forms, arrangements, combinations and constructions of which the invention is capable within the spirit and scope thereof.

More particularly the invention deals with the so-called shipping containers of the insulated types employed in the storage, transportation, and shipping of perishable materials such as foods and the like, characterized by a container body of non-conducting or heat insulating structure (sides and bottom) with an insulating closure or cover for sealing and tightly closing the mouth or open end of the container. Such types of containers generally include a suitable liquid tight lining for the interior thereof such as a metal can or the like, which is mounted and secured in the container as an element or part of the structure thereof, with the open (outer or upper) end thereof accessible to and through the open or mouth end of the container when the container closure or cover is removed. Difficulty is experienced in properly mounting and securing such a liquid tight lining to and in the can, and in efficiently preventing leakage of either air and/or liquid between the lining or can at its open end and the adjacent wall or walls of the container, such leakage materially lowering the insulating efficiency of the container as well recognized by those familiar with these containers.

A main object of the invention is to eliminate the foregoing along with certain other difficulties, through the provision of a construction of container lining of the liquid tight can or receptacle type, and cooperating construction of the container body and bottom by which a proper mounting and securing of the lining in the container, as well as efficiently insulating the lining, and an effec-

tive and efficient seal is formed against leakage into the container between the lining and container structure.

Another object of the invention is to provide a mounting for the container lining which effectively secures and maintains the lining against movement with respect to the container structure or displacement thereof from the container, while obtaining an equal distribution of the load imposed by the contents of the lining or can to the container structure without impairing the efficiency of the seal formed between the lining and adjacent container walls.

A further object of the invention resides in carrying out and securing the foregoing objects and results by means of an arrangement and construction of extreme simplicity calling for a minimum of labor in both constructing and assembling the various elements, to thereby produce a practical commercial structure capable of low cost production.

With the foregoing and certain other objects and results in view, which will be readily apparent from the following description and explanation, the invention consists in certain novel features in construction, and in combinations and arrangements of parts, as will be more fully and particularly referred to and specified hereinafter.

Referring to the accompanying drawings, in which similar reference characters refer to corresponding parts throughout:

Fig. 1, is a vertical transverse section through a container with a lining or can constructed and mounted therein in accordance with the invention.

Fig. 2, is a detail view in vertical section through a portion of the container mouth ring or member and the upper end of the lining or can, showing the securing bead and mouth member receiving the same with the space for the sealing material unfilled.

Fig. 3, is a detail section through the seam or joint at the bottom of the can and a portion of the cooperating container structure.

An insulating shipping container of the general type employed for the storage and transportation of perishable foods, and to which the invention hereof is particularly ap-

plicable, although not limited solely to use with such types of containers, is disclosed more or less diagrammatically in the accompanying drawings purely by way of example for the purpose of explaining and describing the principles and features of the invention. The shipping container 10 illustrated herewith, is characterized by and includes the container body, in the present instance of 10 cylindrical form, but not limited to any particular form or shape, comprising the side wall of insulating material 11, having the mouth member or ring 12 at and forming the open upper end or mouth of the container, 15 and the outer side covering 14, together with the bottom 15 formed of insulating material with the outer covering 16, all providing the insulating container having the interior space or well for receiving the materials to be stored or transported in the container. Any suitable or desired insulating closure or cover (not shown) is of course provided for tightly closing and sealing the open or mouth end of the container, by fitting and sealing onto 25 the annular internal, depressed shoulder or seat 12' formed around the mouth member or ring 12, as will be readily understood by those skilled in this art.

Within the container 10 so formed, a liquid tight lining, such as the metal can or receptacle 20, is snugly and tightly fitted with the open end 21 thereof disposed or terminating a distance below the cover receiving seat or shoulder 12' of mouth ring 12, and 30 aligned with and accessible through the open end or mouth of the container, defined by the mouth member 12. The lower end or bottom of the lining or can 20 rests and is supported upon and insulated against temperature exchange by the insulating bottom 15, as will be clear by reference to the accompanying drawings. With such liquid tight lining or can 20, considerable difficulty has 35 been encountered in securing and mounting the same within the container 10 against movement and displacement under all conditions of use and handling, and in preventing leakage between the upper end 21 of the can or lining 20 and the adjacent container wall, which in the present instance embodies the mouth member 12 and the insulating material 11.

In the example hereof, the mouth ring or member 12 is formed of a suitable material, such as wood, although not restricted to this particular material, having insulating characteristics, and the metal can or other suitable material lining 20, extends a distance over the inner side of this mouth member, to 45 terminate at its open upper end 21 below the cover seat or shoulder 12' of the mouth member. In accordance with the invention, the inner, lower side or face of the mouth ring 12 is cut away inwardly and upwardly a distance through the lower end or edge thereof

to form the recess or groove 22 therearound having the downwardly facing shoulder 23 at the upper (outer) end thereof (see Fig. 2).

Adjacent the upper end 21 of the can or receptacle 20, the can wall is formed in any suitable manner with a circumferential, exterior bead or rib 24 projecting outwardly therefrom in line with the upper end of mouth ring recess 22 and received in this recess beneath and maintained against outward displacement or movement by the shoulder 23, with the rib 24 preferably relatively tightly bearing against and engaging this shoulder 23. Preferably, the upper inner edge 11' of the insulating material 11 of the container wall at 50 the lower end of recess 22 is inclined or rounded inwardly and downwardly from the lower end of recess 22, to can 20 to form in effect a continuation of the recess of decreasing width, as will be clear by reference to Figs. 1 55 and 2 of the accompanying drawings.

The space formed between the wall of can 20 and the insulating wall 11 and mouth ring 12, by the recess 22, is filled by any suitable sealing material, such as asphalt, to form a seal 25 between the mouth member or ring 12 and the upper end 21 of the container lining or can 20, to prevent leakage or passage of air and/or liquid therebetween. The location and formation of the seal 25 around the 60 under side of the rib or bead 24 of can 20, with the upper side of this bead bearing against mouth ring shoulder 23, while the lower end of the can is supported by the container bottom 15, permits of forces tending to outward movement or displacement of the can being taken up directly by the shoulder 23 of the mouth ring 20 from rib or bead 24 without affecting seal 25. The forces tending to downward or inward displacement of can 20 are transmitted thereby directly to the container bottom structure 15, also without affecting or submitting seal 25 to any 65 loads or forces. In this manner the lining or can 20 is secured in position within the container 10, between the container bottom 15 and mouth member shoulder 23, while the seal 25 between the upper end of the can and the container walls is protected against all 70 undesired forces.

The bottom or inner end of the liquid tight lining or can 20, is formed and constructed with a bottom wall 30 having the outwardly turned flange 31 received and suitably locked and sealed within the inwardly and upwardly turned flange 32 of the can side wall, thus forming the depending annular flange joint 33 around the bottom of the can with the bottom wall 30 inset with respect thereto (see Fig. 3). The bottom 15 of the container is formed of a suitable depth of insulating material and at the inner side thereof is formed with an inwardly or upwardly extended central portion or centering disc 34 which provides an annular groove 35 therearound into 80

which the flange joint 33 of the can 20 fits and is suitably sealed if desired, with the disc portion 34 of the container bottom fitting snugly up into the space within flange joint 33 and against the can bottom wall 30. Thus, the cam bottom fits down onto, over the portion 34 of bottom 15 and is maintained between such portion and the container wall 11, against lateral movement or displacement, while being supported on the bottom 15 by the flange joint 33 and the bottom wall 30.

With the foregoing arrangement and construction the liquid tight lining, can or receptacle 20 is secured and maintained in container 20 against movements or displacement, and leakage is prevented between the open upper end thereof and the container wall by the seal 25. The bottom or inner 20 closed end of the can 20 can likewise be sealed with the adjacent wall and bottom of the container if found expedient, the bottom groove 35 providing space for forming such seal, as will be clear by reference to the drawings, and particularly Fig. 3 thereof.

Preferably, as shown by Figs. 1 and 2 of the drawings, the open upper end 21 of the lining or can 20, above the rib or bead 24, is inset into the adjacent face or side wall 30 of mouth member 12, as by slightly cutting away the member, so that the inner surface of the upper end 21 of the can is substantially flush with the inner wall of the mouth member. This eliminates any projection of the upper end edge of can 20, as will be readily understood, although the invention is not so limited.

The construction of the inner can 20 and cooperating structure of container 10 is simple and permits of ready assembly. For example, in assembling a container, the upper end of the can 20 can be inserted from the lower side of the ring, the rib or bead 24 passing freely into position through recess 45 22, the seal 25 can then be formed, after which the insulating wall positioned around can 20, and then the bottom structure 15 applied. The invention thus provides a structure which lends itself to low cost manufacture, and yet which provides a practical and efficient lining or inner can mounting and securing into and as an element of a container, with the can efficiently sealed to prevent leakage between it and adjacent container walls.

It is also evident that various changes, modifications, substitutions and variations might be resorted to without departing from the spirit and scope of my invention, and 60 hence I do not desire to limit myself in all particulars to the exact and specific disclosures hereof.

What I claim, is:

1. In a container, a lining therefore forming a receptacle, a rib formed around said

lining, and a shoulder formed around the adjacent container wall engaging the outer side of said rib.

2. In a container, a lining therefore forming a receptacle therewithin, an exterior rib formed around said lining, the container wall adjacent said rib formed with a recess receiving said rib and engaging the outer side thereof, and a seal formed in said recess at the inner side of said rib.

3. In a container, a lining therefore forming a liquid tight receptacle fitting snugly therewithin, the open end of the container formed by a mouth member, the said lining having a bead formed therearound projecting therefrom at said mouth member, said mouth member formed with a recess receiving said bead and providing a shoulder engaging the outer side of said bead, and a plastic material seal formed in said recess at the inner side of said bead.

4. In a container having a closed bottom wall and a mouth member at the open end thereof, a lining therefore providing a liquid tight open top receptacle fitting longitudinally within the container supported at its inner closed end on the container bottom wall, a bead formed around the open outer end of said receptacle, said container mouth member formed with a recess therein receiving said bead and providing a shoulder engaging the outer side of said bead, and a seal formed in the mouth member recess at the inner side of said bead between the receptacle and the container mouth member.

5. A shipping container, including, an insulating material body having a closed insulating material bottom, a mouth member at the open upper end of the container in continuation of the body, a liquid tight metal lining forming an open-top receptacle fitted snugly within said container supported on the bottom wall thereof against lateral movements thereon, a bead formed around and projecting from said receptacle adjacent the open-top thereof, said mouth member formed with an internal recess therearound receiving said receptacle bead and providing a shoulder engaging the outer side of said bead, and a sealing material in and filling said mouth member recess forming a seal at the inner side of said bead between said receptacle and the mouth member.

6. A shipping container including, an insulating material body having a closed insulating material bottom, a mouth member mounted on the upper edge of said insulating material body in upper continuation thereof defining the open upper end of the container, said mouth member formed with a recess around the inner side thereof through the lower edge thereof to the insulating material body, the upper inner edge of said insulating material body inclined upwardly and outwardly in downward continuation of the

mouth member recess, a liquid tight lining forming an open-top receptacle fitted snugly into said container supported on the bottom wall thereof, a bead formed around and projecting from said receptacle adjacent the open end thereof in line with and received in the upper end of said recess, said bead engaged by the upper wall of the recess, and a sealing material filling said recess below said bead and extending over the inclined edge of said insulating material body to form a seal between the receptacle and the mouth member and container body.

Signed at Kennett Square, county of Chester, Pennsylvania, this 12th day of December, 1927.
